Primary Examiner — Sandra Snapp*Assistant Examiner* — Katherine Glennon(74) *Attorney, Agent, or Firm* — Banner & Witcoff, Ltd.(57) **CLAIM**

The ornamental design for a shoe upper, as shown and described.

DESCRIPTION

FIG. 1 is a front perspective view of a shoe upper showing my new design;

FIG. 2 is a side view thereof;

FIG. 3 is a rear perspective view thereof; and,

FIG. 4 is an enlarged view of the claimed region in FIG. 2, shown in isolation.

The dot-dash lines immediately adjacent to the shaded area represent unclaimed boundaries of the design. The dot-dash lines showing the remainder of the shoe are for environmental purpose only and form no part of the claimed design. The contrast in shading represents a contrast in appearance only and does not represent any particular color, material, texture or finish.
